UNITED STATES PATENT OFFICE.

ANDREW C. BAKER, OF ALBION, MICHIGAN.

DUMP-WAGON.

1,102,852.

Specification of Letters Patent.

Patented July 7, 1914.

Application filed October 18, 1913. Serial No. 795,918.

To all whom it may concern:

Be it known that I, ANDREW C. BAKER, a citizen of the United States of America, residing at Albion, in the county of Calhoun 5 and State of Michigan, have invented certain new and useful Improvements in Dump-Wagons, of which the following is a specification, reference being had therein to the accompanying drawings.

10 This invention relates to dump wagons and more particularly to certain improvements in connection with my Patent 967154, granted August 16, 1910.

15 My invention aims to provide positive and reliable means, in a manner hereinafter set forth, for expeditiously opening and closing the discharge doors of the wagon body.

20 My invention further aims to provide a door operating mechanism that is located where it can be easily operated without subjecting the discharge doors or gates of the dump wagon to stress and strains, the connection with the doors or gates being such that they are supported in a horizontal position against accidental displacement when 25 the vehicle is loaded.

With the above and other objects in view, the invention resides in the novel construction, combination and arrangement of parts 30 to be hereinafter specifically described and claimed.

Reference will now be had to the drawings, wherein—

Figure 1 is a longitudinal sectional view 35 of a dump wagon in accordance with this invention. Fig. 2 is a cross-sectional view of the same. Fig. 3 is a rear end view of the wagon, and Fig. 4 is a view of the front end of the wagon.

40 In the drawings 1 denotes a conventional form of running gear and arranged upon the running gear are front and rear platforms 2 and 3. These platforms support the ends of side walls 4 forming the sides of a box 45 adapted to contain dumpable material. The side walls 4 are connected by inclined end walls 5 and arranged upon the upper edges of the walls 4 and 5 are the walls 6 and 7 of an extension frame adapted to increase the

50 capacity of the box. The walls 6 are stationary and are held by straps 8 or other fastening means, carried by the walls 5. The walls 7 are disposed at an angle and at the ends of said walls are inwardly projecting V-shaped arms 9 that are pivotally connected, as at 10 to the inner sides of the walls

6. The walls 7 can be swung upwardly relatively to the side walls 4 of the box and it is through the medium of the walls 7 that a heaped load can be discharged. 60

Arranged upon the front and rear platforms 2 and 3 are longitudinally alining bearings 11 and mounted in these bearings is a central tubular hinge member 12. Loosely mounted upon this member are the 65 strap hinges 13 of center bottom doors or gates 14.

Connected to the lower edges of the side walls 4 by hinges 15 are side doors or gates 16 that coöperate with the center door or gates 14 in forming the bottom of the box. The doors 14 and 16 are adapted to swing 70 downwardly whereby the contents of the box can be quickly discharged, and as a shield for the central hinge member 12, the walls 75 5 of the box are connected by a longitudinal deflector 17.

The side walls 4, at the ends thereof, are provided with transversely alining bearings 18 and journaled in said bearings are rock 80 shafts 19 and 20. Mounted upon the rock shaft 19 are cranks 21, 21^a and 22, the cranks 21 and 21^a having chain connections 23 with the rear ends of the discharge doors 14 and 16. 85

The single crank 22 is connected to a chain 24 that extends under a sheave or grooved pulley 25 revolubly supported by a hanger 26 forming a part of the bearing 11 upon the rear platform 3. The chain 24 90 extends through the central tubular hinge member 12 and under a sheave or pulley 27, journaled in a hanger 28 forming part of the bearing 11 upon the forward platform 2. The chain 24 has the forward end thereof 95 connected, as at 29, to a yoke 30, said yoke having its ends loosely mounted in strap bearings 31 provided therefor upon the forward platform 2.

The rock shaft 20 has a set of bell cranks 100 32 that are connected by chains 33 to the forward ends of the discharge doors 14 and 16. The rock shaft 20 also has a single crank 34 that is connected by a chain 35 to the yoke 30. 105

The forward edge of the platform 2 has bearings 36 for the trunnions 37 of the locking lever 38. The upper end of the locking lever 38 has an offset portion 39 to receive the tread bar 40 of the yoke 30, whereby said yoke can be locked with the discharge doors 14 and 16 in a closed position. The 110

upper end of the locking lever 38 terminates in a tread piece 41 which permits of the driver of the vehicle quickly swinging the locking lever out of engagement with the 5 yoke 30. The lower end of the locking lever 38 extends into a spring guide 42, carried by the platform 2. Encircling the spring guide 42 is a coiled compression spring 43 that engages the lower end of the locking 10 lever 38 and holds the offset portion 39 of said lever normally in engagement with the tread bar 40 of the yoke 30.

Mounted upon the forward edge of the platform 2 is a bearing 44 for the pivoted 15 hand lever 45, the purpose of which will presently appear.

As illustrated in Fig. 1, the discharge doors 14 and 16 are locked in a closed position and either one of the levers 38 or 45 20 can be used for releasing the doors 14 and 16. To quickly discharge the contents of the box it is only necessary to press upon the tread piece 41 of the lock lever 38. This is best accomplished by holding the lever 45 25 against the yoke 30 until the locking lever 38 has been shifted clear of the yoke, and then by releasing the lever 45 the discharge doors 14 and 16 will quickly open. To gradually discharge the load within the box 30 the lever 45 is held onto and the yoke 30 allowed to gradually swing and lower the doors 14 and 16.

The levers 38 and 45 are located centrally of the forward platform 2 in proximity to a 35 driver's seat 46, and the arrangement of the levers is such that the discharge of material from the box of the wagon can be easily controlled. The yoke 30 serves functionally as a foot rest for a driver and cannot be accidentally shifted by reason of the locking lever 38 being held normally in engagement therewith by the compression spring 43.

While in the drawings there is illustrated a preferred embodiment of my invention, it 45 is to be understood that the structural elements are susceptible to such changes, as in the size, shape and proportion as falls within the scope of the appended claims.

What I claim is:

50 1. In a dump wagon, a box, a tubular hinge member longitudinal of said box,

hinged center doors carried thereby, side doors carried by said box and coöperating with said center doors in forming the bottom of said box, rock crank shafts at the 55 ends of said box and having connections with said doors, and an operable yoke at the end of said box and connected to said crank shafts with one of its connections extending through said member whereby the doors can 60 be evenly moved.

2. In a dump wagon, a box, platforms at the ends of said box, a tubular hinge member supported by said platform, hinged center bottom doors carried by said member, 65 hinged side bottom doors carried by said box, rock crank shafts connected to said doors, and a pivoted yoke supported by one of said platforms and having connection with said crank shafts with one of said connections extending through said member.

3. In a dump wagon, a box, a tubular hinge member arranged longitudinally of said box, discharge doors hinged thereon, side doors carried by the said box and coöperating with said discharge doors in forming the bottom of said box, and means 75 operable at one end of said box with a connection through said member to the opposite end of said box for evenly moving the 80 ends of the said doors.

4. In a dump wagon, a box, a tubular hinge member arranged longitudinally of said box, discharge doors hinged thereon, and means operable at one end of said box 85 with a connection through said member to the opposite end of said box for evenly moving the ends of said doors.

5. In a door operating mechanism, hinged doors, a tubular member forming a hinge for some of said doors, and rock crank shafts at the ends of said member and having connections with all of said doors and a connection with each other that extends through said member.

90 In testimony whereof I affix my signature in presence of two witnesses.

ANDREW C. BAKER.
